JAMES T. WATKINS, OF SANTA CLARA, CALIFORNIA.

Letters Patent No. 79,880, dated July 14, 1868.

IMPROVEMENT IN GANG-PLOW.

The Schedule referred to in these Letters Patent and making part of the same.

TO ALL WHOM IT MAY CONCERN:

Be it known that I, JAMES T. WATKINS, of Santa Clara, county of Santa Clara, State of California, have invented an Improved Gang-Plow; and I do hereby declare the following description and accompanying drawings are sufficient to enable any person skilled in the art or science to which it most nearly appertains to make and use my said invention or improvements without further invention or experiment.

The nature of my invention is the construction of an improved gang-plow, having for its office, first, a novel method of raising and lowering the plows, either separately or collectively, so as to entirely clear the ground; second, a device by which the depth of the furrows is determined and regulated; it also relates to a simple mode of raising and lowering the furrow-wheel, so that the machine shall at all times stand horizontal, whether at work, or passing from one point to another.

The machine is mounted upon three wheels, the steering-wheel being placed behind, and so mounted as to follow easily in the furrows. Its periphery is made convex, in order to give it a hold upon the ground, and to guide more easily, as well as to make it self-cleaning. The same form is used for the other wheels.

To more fully explain my invention, reference is had to the accompanying drawings, forming a part of this specification, of which—

Figure 1 is a plan of my plow.

Figure 2 is a side elevation, with a section through X X.

Similar letters of reference in each of the figures indicate like parts.

A is a strong framework of wood, mounted upon two bearing-wheels, B B', and supporting the shafts or axles C C, to which the plows are attached. These axles turn in boxes, D, on the frame. Iron blocks E E' are attached to the axles by set-screws F F, and the shanks G G' of the plows H H pass entirely through these blocks, and are held by set-screws I, so that the plows may be elevated or lowered, at pleasure. Bent arms J and J' extend forward from the blocks E E', and have the regulating-screws K K' passing vertically through their front ends, the screw K' resting on the bar I, while the screw K rests upon the block E''. By turning these screws to the right or left, the plows are either raised or lowered, so as to vary the depth of the furrows, while by the wedges *a a* the plows may be turned to or from the land.

The arm J is bent upward far enough to form a convenient handle at M, by which the driver can raise the plow. Another bent arm, N, extends forward from the block E'', and has a loose connecting-rod, O, which can be attached to the lever-handle M, so that both plows can be raised to clear obstructions, or one may be raised by detaching this rod. A catch, P, is attached to the frame, so that, when desired, the plows may be permanently raised from the ground, the catch holding up the arm J', and by means of that the arm J.

The wheel B is mounted upon a stationary axle, extending partly across the frame, while the axle of the wheel B' is bent at right angles, so as to extend upwards at the side of the frame. At the top it is again bent, so as to form a strong nut, R, over the frame. Through this nut the screw S passes vertically, its lower end resting upon an iron plate on the frame, while the upper end may be provided with a crank or hand-wheel, V, by which to operate it. The screw passes, with a shoulder, through the standard T, by which it is supported, so as to move the wheel and its axle up and down when turned.

By this arrangement the furrow-wheel B can be lowered, so as to level the machine, when it is not at work, or it may be raised so as to be level when moving from place to place on the road, and the plows can be thrown up at the same time, and be retained by the catch P, thus making a simple and easily-regulated plow.

The wheel B B' and the centre-wheel b are made convex, as shown at C C, so that they will run steadier and the soil will not adhere to them, thus making them self-cleaning.

Having thus described my invention, what I claim, and desire to secure by Letters Patent, is—

1. The plows H H, in combination with the blocks E E', the holding-screws I I, by which the plows are adjusted, and the wedges *a a*, constructed and arranged substantially as described.

2. The blocks E E' mounted upon the axles C C', and the bent arms J J', with the set-screws K K' for regulating the depth of the furrows, substantially as described.

3. The bent arm N and connecting-rod O, with the handle M and the catch P, for disengaging the plows, substantially as described.

4. The bent axle R, with the nut R' and the screw S, for raising and depressing the furrow-wheel, substantially as described.

In witness whereof, I have hereunto set my hand and seal.

J. T. WATKINS. [L. s.]
